CLOSURE INSPECTING DEVICE

Clair Mowrer, Lancaster, Pa., assignor to Armstrong Cork Company, Lancaster, Pa., a corporation of Pennsylvania

Application May 29, 1937, Serial No. 145,635

6 Claims. (Cl. 209—88)

This invention relates to a closure inspecting device which is particularly adapted for segregating and classifying closures after sealing liner inserting operation. The device is preferably so constructed and arranged that those closures which, upon inspection, are found to be satisfactory for use are delivered to one station (or are delivered to other apparatus if subsequent operations are to be performed thereon) and those closures which are defective by reason of the sealing liners being broken, of less thickness than the predetermined standard, or which have, through failure of the inserting machine or otherwise, been fed to the inspection device without liners, are delivered to a second station where they may be salvaged or destroyed. A device of this type is particularly useful in the inspection of crown shells wherein it is essential that the liners be of accurate thickness.

The device comprises means for supporting closure members to be inspected, an inspecting member adapted to enter closures positioned on said support and to engage the sealing liners therein, control means responsive to the position of the inspecting member and effective for determining further movement of the closures from the inspecting station or for initiating a suitable signal, and means for sequentially presenting closure members to the inspection member. The device is preferably associated with assembling, spotting, paraffining or other closure fabricating equipment in order to combine the inspection operation with another operation, thus avoiding duplicate handling of the members to be inspected. If the inspecting device be associated with an assembly or spotting machine, the usual finger bar moving mechanism may be utilized to sequentially present the closure members for inspection. If it be desired to deliver the rejected closures to a suitable bin or receptacle, a portion of the supporting rails along which the closures are sequentially moved by the finger bar may be made retractile, and retraction thereof effected by the control means. Adjusting mechanism may be provided so that the device may accommodate closures of different sizes and liners of different thicknesses.

Referring to the drawing which illustrates one embodiment of my invention,

Figure 1 is an end elevation, partly in section and partly broken away, showing my inspection device mounted for operation upon a crown seal fabricating machine including a finger bar moving mechanism;

Figure 2 is a sectional view taken on the line II—II of Figure 1; and

Figure 3 is a sectional view taken on the line III—III of Figure 1, showing the inspecting plunger.

The finger bar feeding mechanism comprises a toothed member 2 fastened to a slide 3 adapted for oscillatory and reciprocatory movement upon a bearing channel 4. Teeth 5 provided in the member 2 are shaped to engage the skirts of a series of closures 6 which are supported for movement in a step-by-step manner along the machine upon spaced rails 7 and 8 having recessed portions 9 and 10 to receive the flanged portion of the closure skirt. Cover plates 11 and 12 overlie the guide rails 7 and 8 and prevent vertical displacement of the shells. Coincidental oscillatory and reciprocatory movements are imparted to the member 2 by cranks such as shown at 13, to which member 2 is pivoted by pin 14; the movement imparted by the crank 13 being such that the closures 6 are sequentially presented to an inspecting member 15 mounted on a frame 16 spanning the finger bar feeding mechanism and lie at rest in such position for a period of time while inspection is being effected.

The inspecting member 15 (Figure 3) comprises a spring urged headed plunger 17 movable within a sleeve 18 threaded into support 16 and secured in position by means of a lock nut 19. Portion 20 of the plunger 17 is of reduced diameter and moves within a sleeve 21, which sleeve in turn moves within sleeve 18. A guide collar 22 for a bifurcated rocker arm 23 encircles the portion 20 of the plunger 17, is freely movable thereon, and rests on top of sleeve 21. Upon rocking motion of arm 23, vertical motion is imparted to sleeve 21 which in turn imparts a similar motion to plunger 17 through a spring 24 positioned between the head of plunger 17 and the lower end of sleeve 21. A return spring 25 normally urges collar 22 into engagement with contact bar 26 threaded to plunger 17 and locked by a nut 27. Spring 24 normally urges sleeve 21 into engagement with collar 22.

Reciprocatory movement in a vertical direction is imparted to the inspecting member 15 by the rocker arm 23 which is pivoted at 28 to the frame member 16. A cam 29 is provided on slide 3 and is engageable with a cam roller 30 secured to the end of arm 23. Upon movement of slide 3 imparted by crank 13, cam 29 is brought into engagement with the roller 30; the contouring of cam 29 being such that arm 23 is moved to the position shown in dotted lines in Figure 1 and

maintained in such position for a short period of time, corresponding to the period in which the closures 6 are at rest on the support. Coincidentally with rocking of arm 23, collar 22 is moved downwardly, thus moving sleeve 21 within sleeve 18 and compressing spring 25. Plunger 17 is likewise moved downwardly—sleeve 21 operating through spring 24 to impart such movement. So long as there be no restriction in the path of plunger 17, the contact bar 26 follows collar 22, but upon engagement of plunger 17 with a liner disposed within the closure under inspection, movement of plunger 17 ceases and continued movement of collar 22 results only in compression of spring 24. Since contact bar 26 is fixed to plunger 17, it will maintain its position with respect thereto. The device is so adjusted that contact 31, which is adjustably secured to contact bar 26, is out of engagement with a similar contact 32, attached to an insulated support 33, when plunger 17 is in engagement with a liner of proper thickness disposed within the closure under inspection, but contacts 31 and 32 will lie in engagement if the liner in the closure under inspection be of less than the required thickness or if the closure has no liner disposed therein.

From the foregoing, it will be clear that as the finger bar mechanism moves closures sequentially into the inspection station, the inspecting plunger is moved into the closure arriving at the inspection station and dwells therein until the finger bar is about to move the inspected closure therefrom and present the next sequential closure thereto, and that the inspecting plunger actuates a pair of contacts, engagement thereof being effected if the closure is found to be defective, but so arranged as to be out of contact when satisfactory closures are inspected.

The contacts may be used to effectuate any desired signal or control. In my preferred embodiment, a retractile rail section 34 is provided in order that rejected closures will be removed from the supporting rails and discarded. The retractile section 34 is guided in ways 35 provided in a finger bar frame 36 and is secured by a link 37 to an iron core 38 of a solenoid coil 39. Link 37 passes through frame 16 and the rail section 34 is normally urged into alignment with the adjacent rail sections by a spring 40 disposed between frame 16 and a collar 41 secured to the link 37, movement of the rail section 34 being limited by stops 42, shown in Figure 2. This figure shows the finger bar mechanism in an intermediate position in order to clearly illustrate the alignment of the rail sections. During inspection, the closures under inspection will be disposed wholly within the retractile rail section in order that upon retraction thereof the closure may fall by gravity into a chute 43 communicating with a suitable receptacle or bin.

Solenoid coil 39 is secured within bracket 44 forming part of frame 16 and an adjustable stop 45 is positioned within the coil to limit movement of the core 38 upon energization of the coil 39. The magnitude of movement necessary for retracting the rail section 34 in an amount sufficient to permit the closures 6 under inspection to fall into chute 43 depends upon the type of closures being inspected and the length of the flange or bead disposed within the recesses 9 and 10 of the rail sections. For that reason, an adjusting screw 45' is provided to properly position stop 45.

Energization of coil 39 is effected only after contacts 31 and 32 are in engagement; the circuit being from one side of a source of current S

through lead 46 to contact bracket 47, through bolt 48 (which is threaded in bracket 47), contact bar 26 to contact 31, and from contact 32 through lead 49 to the coil 39. The other side of the current source S is connected to the coil by a lead 50. By utilizing bolt 48, a flexible connection between bracket 47 and reciprocable contact bar 26 is eliminated. Bolt 48 also provides an adjustable limiting stop for the inspecting member 15; the head 51 of the bolt limiting upward movement of the contact bar 26.

If desired, a condenser may be provided across the contacts 31 and 32 in order to minimize arcing but if a low current solenoid be employed this will not be necessary even though the device be adjusted to reject those closures having liners which are a few thousandths of an inch under size. Under such conditions, the contacts will come within a corresponding distance from each other at each inspecting step.

In the operation of the illustrated control, when contacts 31 and 32 engage, circuit is completed for current supply to solenoid 39 and core 38 is magnetically drawn within the coil and into engagement with the limiting stop 45, rail section 34 is retracted against the pressure of spring 40 and the closure 6 being inspected falls by gravity into chute 43 which delivers it to a suitable receptacle. The spring 40 returns the rail section 34 to its normal position upon deenergization of coil 39 effected upon movement of contacts 31 and 32 out of engagement upon elevation of the inspecting member 15 as heretofore described.

The device is so constructed that it may be removed as a unit from the machine to which it is applied by removing bolts 52 and 53 and a pin 54 which secures link 37 to rail section 34. The device is conveniently adjustable to within narrow limits and may be readily adapted for operating upon different types of closures. For example, by substituting for rails 8 and 9 a pair of rails having recesses to accommodate the bead on a single shell continuous thread closure, the inspection device may be utilized for liner inspection of such closures. Finer inspection may be had with the device of this invention than that attainable heretofore where inspectors closely examined the closures as they passed before them on a suitable conveyor. The labor savings incident to the use of the device are obvious; the labor costs being entirely eliminated where the device is incorporated with other closure fabricating equipment.

While I have described and illustrated the preferred embodiment of my invention, it will be understood that the invention is not so limited but may be otherwise embodied within the scope of the following claims:

I claim:

1. A closure inspecting device comprising a closure support, a finger bar for sequentially moving closures along the support, means for imparting coincidental oscillatory and reciprocatory movement to said finger bar, an inspecting member mounted for vertical reciprocatory movement into and out of closures on said support, a rocker arm engageable with the inspecting member to impart vertical reciprocatory motion thereto, a cam on the finger bar for imparting rocking motion to said arm and control means responsive to the position of the inspecting member within the closure.

2. A closure inspecting device in accordance with claim 1 in which the inspecting member is adjustably supported to permit predetermination of the position to be assumed by said inspecting

member within said closure to initiate said control.

3. A closure inspecting device comprising a rigid support adapted to span a pair of closure supporting tracks, an inspecting member mounted on said support above said tracks, a pivoted rocker arm mounted on said support and engageable with said inspecting member to impart vertical reciprocatory motion thereto, electrical control means, a contact fixed to said support, a contact carried by said inspecting member and engageable with said fixed contact upon vertical motion of said inspecting member to initiate said control means, a member having coincidental oscillatory and reciprocatory movement for conveying closures in intermittent steps along said tracks to bring the same sequentially into position to be engaged by said inspection member, and means on said conveying member engageable with said arm to impart rocking movement thereto.

4. A closure inspecting device in accordance with claim 3 in which the inspecting member, rocker arm, contacts and control means are all affixed to the support so as to be removable from the closure supporting track mechanism as a unit.

5. A closure inspecting device comprising a closure support, a portion of said support at an inspection station being retractile to permit automatic removal of inspected closures from said

support, means yieldingly urging said retractile portion to supporting position, an inspecting member adapted to engage a closure on said support at the inspection station, a pivoted rocker arm engageable with said inspecting member to impart a predetermined, vertical reciprocatory motion thereto, electrical control means for retracting said retractile portion of said support to eject an inspected closure therefrom, a contact carried by said inspecting member and engageable with a fixed contact to initiate said control means upon vertical motion of said inspecting member to a predetermined position, a member having coincidental oscillatory and reciprocatory movement for sequentially moving closures along said support, and means on said last named member engageable with said arm to impart rocking movement thereto.

6. A closure inspecting device in accordance with claim 5 in which the inspecting member comprises a guide, an inspecting finger slidable within said guide, a control initiating member carried by and movable with said finger, an operating slide encircling said finger, and yielding means disposed between said slide and one end of said finger, whereby movement of said finger is arrested upon its engagement with a closure on said closure support.
